(57) **CLAIM**

The ornamental design for a ceiling fan, as shown and described.

DESCRIPTION

FIG. 1 is a top perspective view of a ceiling fan, showing our new design;

FIG. 2 is a bottom perspective view of the ceiling fan of FIG. 3;

FIG. 3 is a side view thereof of FIG. 3;

FIG. 4 is another side view thereof of FIG. 3;

FIG. 5 is a bottom view thereof of FIG. 3;

FIG. 6 is a top view thereof of FIG. 3;

FIG. 7 is an enlarged top perspective detail view thereof, showing the portion of the ceiling fan encircled by dash-dot-dash lines in FIG. 1; and,

FIG. 8 is an enlarged detail side view thereof, showing the portion of the ceiling fan encircled by dash-dot-dash lines in FIG. 3.

Portions of the ceiling fan shown in broken line form no part of the claimed design.

1 Claim, 8 Drawing Sheets
